HENRY WILLIAM SHORT, OF LONDON, ENGLAND.

BOOT-LACE.

1,062,511.

Specification of Letters Patent. Patented May 20, 1913.

Application filed June 19, 1912. Serial No. 704,559.

To all whom it may concern:

Be it known that I, HENRY WILLIAM SHORT, a subject of the King of Great Britain, and resident of 238 Seven Sisters road, London, England, scientific-instrument maker, have invented a certain new and useful Improvement in Boot-Laces, of which the following is a specification.

Heretofore it has been customary to leave 10 the ends of boot and shoe laces free and to tie said ends together on the completion of the lacing operation.

The primary object of the present invention is to obviate the necessity of such tying, 15 and to provide a neat finish for the lace; and this is accomplished by the use of a lace which in effect is endless and of approximately the exact length required only for engaging with all the hooks, the extremities 20 of the lace (after the length of lace required has been once for all ascertained) being permanently connected together by means of a flexible and extensible spring-coupling:

In the accompanying drawings, Figure 1 25 is a front view of a lace-up boot closed by means of the improved lace, the boot being shown as mounted on a boot-tree. Fig. 2 is a perspective view of a similar boot, the upper or hooked portion of the laced closure 30 being unfastened to allow of the boot being put on. Fig. 3 is a view of the improved lace, shown separately (on a larger scale) together with the spring-coupling connecting its extremities; and Fig. 4 shows the 35 spring-coupling alone, this being viewed in directions at right angles to one another in Figs. 3 and 4 respectively. Figs. 5 and 6 are perspective views of the spring-coupling (drawn to a larger scale than Figs. 3 and 4), 40 respectively illustrating successive stages in the manufacture of the coupling in its preferred form.

The laced closure, throughout its lower portion (which is commonly kept permanently fastened), is effected by passing the lace *a* through eyelets *b* arranged in a series of pairs at opposite sides of the opening *c* of the boot; while the closure, throughout its upper or final portion (which alone is 50 commonly unfastened when the boot is to be put on or taken off), is as a rule effected by passing each member *a*¹ and *a*² (Figs. 2 and 3) of the double-ended lace *a* from side to side of the opening *c* so as to engage with 55 hooks *d* arranged (in continuation of the rows of eyelets *b*) in a further series of

pairs at opposite sides of said opening; the respective members *a*¹ and *a*² of the lace crossing one another between successive pairs of the hooks *d* and each member *a*¹ 60 and *a*² engaging with the hooks at alternate sides of the opening *c*; all these features being as usual.

For the purpose of the present invention the respective members *a*¹, *a*² of the lace 65 should be of equal length and just long enough to engage with the last or uppermost pair *d*¹ of the hooks when the lacing is completed, and to permit of attachment to the spring-coupling by means of which the extremities of the lace are permanently connected together. On reference to Fig. 1 it 70 will be seen that when the boot is laced-up, the spring-coupling constitutes a cross-bar which engages over the tops of the uppermost pair *d*¹ of the hooks. In Fig. 2 the splaying apart of the flaps of the boot prevents the hooks being fully seen, but their 75 positions are indicated by the eyelets whereby they are secured in position as usual.

The spring-coupling comprises a coiled spring *e* of a length only sufficient to approximately bridge the distance separating the hooks of a pair, and a pair of eyes *f*¹, *f*² formed on the ends of the coil *e* and adapted 80 to give passage to the respective members *a*¹, *a*² of the lace; both of said eyes *f*¹, *f*² extending in substantially one plane, which 85 is parallel to the axis of the coil *e* and approximately tangential to the surface of 90 the latter, as indicated.

Each member *a*¹ or *a*² of the lace *a* is attached to the spring-coupling by being threaded through the corresponding eye *f*¹ or *f*², knotted as at *g* to prevent complete retraction through the eye, and drawn back until the knot *g* engages the eye, the raw extremity of the lace (indicated at *h* in Fig. 3) 95 being thereupon tucked into the tubular spring-coil *e* so as to become concealed as indicated at the left-hand side of Fig. 3.

In the manufacture of the spring-coupling, the eyes *f*¹, *f*² are preferably each formed by a terminal convolution of the coil *e* being bent down out of its original position so as to occupy the position already described and clearly shown in Fig. 3; the convolutions thus displaced forming loops as clearly shown in Fig. 4. The mere operation of thus bending down each terminal convolution out of its original position 105 would, however, leave the extremity of the 110

spring wire (whereof the coil e is formed) exposed at what may be regarded as the outer (or lower) side of the eye f^1 or f^2 as indicated at j in the perspective view, Fig. 5; an arrangement liable to prove objectionable on account of the tendency of the exposed raw extremity of the cut wire to catch against and injure the fingers or any object with which the spring-coupling may be brought into contact. In order to overcome this defect, it is preferred to subsequently displace each extremity of the wire from the position indicated at j , Fig. 5, to that indicated at k , Fig. 6. This further operation has the effect of reversing the direction of winding of the loop which constitutes the eye, and bringing each extremity of the wire from the outer (or lower) side to the inner (or upper) side of the corresponding eye f^1 or f^2 , in which new and final position the raw extremity of the wire is concealed and completely shielded by the knot g of the lace when the latter is combined with the spring-coupling in the manner already described.

In the event of the lace a stretching when in wear, its effective length may be permanently shortened by shifting one or both of the knots g farther up the lace. Should this not be convenient at the moment, however, various simple expedients may be resorted to during the lacing operation itself. Thus, for example, where only a slight amount of shortening is desired, the members a^1 , a^2 of the lace may, between two or more successive pairs of hooks d , be twisted about one another and thereafter brought back to the original side of the opening c , instead of being led right across the opening as shown in Fig. 1. Or, where a greater amount of shortening is necessary, each member a^1 , a^2 of the lace may be wound around both hooks of a pair, and led back to that hook of the pair with which it first engaged, before the lacing is continued. On the other hand, in the event of the lace at any time proving too short to reach to the last or uppermost pair d^1 of hooks when the lacing operation is performed in the normal manner, the spring-coupling may yet be made to engage over said last pair of hooks either by omitting to engage the respective lace-members with a pair or pairs of hooks below the uppermost pair d^1 , or by omitting (once or more often) to cross the respective lace-members from side to side of the opening c ; each member a^1 and a^2 of the lace in the latter case being preferably made to engage (say) two hooks in direct

succession on the same side of the opening 60 of the boot.

As the spring-coil e is both flexible and extensible, it will be evident that the spring-coupling is adapted, while yielding with the movement of the foot, to maintain the tension of the lace and the security of the closure effected thereby.

Claims.

1. An improved endless shoe lace consisting of a lace proper having its ends provided with knots, and a spring coupling for the ends of the lace which is formed of a wire coil having its ends formed as eyes of less diameter than the knots, as described.

2. The combination with a lace shoe having hooks on its opposite flaps, of a lace adapted for application to the shoe in the usual way and provided with knots adjacent to its ends, a spring coupling for said ends, the same consisting of a spirally coiled spring having its ends formed as eyes adapted for application to the lace, but made of less diameter than the knots, as described.

3. The combination with a spring-coupling consisting of a coiled spring provided with eyes at its opposite ends, both of said eyes extending in substantially one plane which is parallel to the axis of the spring-coil and approximately tangential to the surface of the coil, of a boot-lace whose members are threaded through the respective eyes of the spring-coupling and provided with knots to prevent complete retraction of said members through the eyes, substantially as described.

4. The combination with a spring-coupling consisting of a coil of spring wire whereof the terminal convolutions are bent out of their original positions to constitute 100 eyes, said terminal convolutions when thus displaced extending both in substantially one plane which is parallel to the axis of the coil and approximately tangential to the surface of the latter, and each extremity 105 of the wire being further displaced so as in effect to reverse the direction of winding of the convolution which forms the corresponding eye, of a boot-lace whose members are threaded through the respective eyes of the 110 spring-coupling and provided with knots to prevent complete retraction of said members through the eyes, substantially as described.
